UNITED STATES PATENT OFFICE.

WILLIAM KUYKENDALL, OF LOS ANGELES, CALIFORNIA.

CLEANING COMPOUND.

No Drawing.

Application filed September 7, 1923. Serial No. 661,521.

To all whom it may concern:

Be it known that I, WILLIAM KUYKENDALL, a citizen of the United States, residing at Los Angeles, in the county of Los Angeles and State of California, have invented new and useful Improvements in a Cleaning Compound, of which the following is a specification.

This invention relates to cleaning compounds and has for its object to provide a cleaning compound especially effective for cleaning surfaces of toilets, basins, baths and of tile and of porcelain and enamel finishes, and further, which will be effective for cleaning natural and artificial stone surfaces.

In preparing my cleaning compound I prefer to make a mixture consisting of 1 pound of oil of mirbane and 1 gallon of coal oil, which mixture may be termed the first mixture. I also make a mixture consisting of 1 pint of liquid bluing and 1 gallon of water, which mixture may be the second mixture.

To 1 ounce of the first mixture I add 3 ounces of the second mixture and further add 28 ounces of hydrochloric acid, 1 ounce of sodium chloride, 1 ounce of vinegar, 1 ounce of lemon juice and enough water to make 1 gallon of the cleaning compound. The ingredients of my compound are mixed in the ordinary manner of mixing, no particular order being observed and unusual methods employed.

It will be understood that any one of the ingredients lemon juice, salt or vinegar may be used singly in making up the compound without the inclusion of the other two.

Further embodiments, modifications and variations may be resorted to within the principle of the invention.

What is claimed is:

1. A cleaning compound consisting of hydrochloric acid, sodium chloride, vinegar, water and coal oil.

2. A cleaning compound consisting of hydrochloric acid, sodium chloride, vinegar, lemon juice, water, coal oil and bluing.

In testimony whereof I have signed my name to this specification.

WM. KUYKENDALL.
